UNITED STATES PATENT OFFICE.

HECTOR RABEZZANA, OF FLINT, MICHIGAN, ASSIGNOR TO A-C SPARK PLUG COMPANY, OF FLINT, MICHIGAN, A CORPORATION OF MICHIGAN.

MACHINE FOR ASSEMBLING SPARK PLUGS.

Application filed April 17, 1922. Serial No. 553,605.

To all whom it may concern:

Be it known that I, HECTOR RABEZZANA, a subject of the King of Italy, and a resident of Flint, county of Genesee, and State of Michigan, have invented certain new and useful Improvements in Machines for Assembling Spark Plugs, of which the following is a full, clear, concise, and exact description, such as will enable others skilled in the art to which the invention relates to make and use the same, reference being made therein to the accompanying drawings, which form a part of this specification.

My invention relates to the assembling of the several parts which collectively form a spark plug, and the principal object thereof is to provide a machine having various of the characteristics of a press operated by air under pressure and by the use of which the parts which constitute a spark plug may be better and more expeditiously assembled than has heretofore been the case.

My invention relates particularly to a machine or press designed to perform a preliminary assembling operation upon spark plugs of the type wherein the porcelain insulating member is held in place within the metallic shell of the plug by an inturned flange, thus providing a single piece plug the insulating member of which cannot be removed from the shell. In such plugs lower and upper yieldable gaskets are interposed between shoulders upon the insulating member and a lower ledge in the shell, and between the inturned flange at the upper end thereof; and if the several meeting surfaces at the joints thus formed are not in intimate contact with one another when the holding flange is turned inward the turning in operation may fail to take up the looseness at the joints, with the result that the meeting surfaces at the several joints will not be pressed into proper contact and leakage of gas past or through the joints is likely to develop when the plug is in use. My invention, therefore, is designed to obviate this objectionable feature by providing for the forcing of the insulating member downward into the casing of the plug thus compressing the lower gasket, and for forcing the upper gasket into intimate contact with the upper shoulder of the insulator and

adjacent inner wall of the shell cavity, as steps preliminary to the turning inward of the holding flange onto the upper gasket by 55 another machine; thus providing a plan wherein the gaskets are fully compressed prior to the final step of turning the holding flange inward and in which such turning in operation is not relied upon at all to produce proper contact between the meeting surfaces at the gaskets and proper gas tight joints between the insulating member and the shell or casing of the plug.

A further object of my invention is to 65 provide a device for the purpose above explained wherein the mechanisms for subjecting the lower and upper gaskets to pressure are independent of one another, so that each operates independently of the other to compress the gasket which it is designed to compress; and a still further object of my invention is to provide a device, machine or press wherein the pressure applied to the lower gasket may be made greater than the 75 pressure applied to the upper gasket in the preliminary assembling of the parts as hereinbefore explained.

With the above and other objects of invention in view, my invention consists in 80 the improved spark plug assembling device illustrated in the accompanying drawings and hereinafter described and finally claimed; and in such variations and modifications thereof, within the scope of the 85 concluding claims, as will be obvious to those skilled in the art to which my invention relates.

In the drawings accompanying and forming a part of this specification and wherein 90 the preferred embodiment of my invention is illustrated:

Figure 1 is a view showing my invention in side elevation for the most part, but sectioned in various places in order to enable 95 the invention to be better understood.

Figure 2 is a similar view showing my invention in elevation and as seen from a position in front thereof.

Figure 3 is a fragmentary view showing 100 the toggle mechanism shown in Figures 1 and 2 in its collapsed instead of straightened condition, as in said figures.

Figure 4 is a view showing the air cylin-

ders of my invention partly in plan and partly in section, together with the valve for controlling the flow of air into and out from said cylinders.

5 Figure 5 is a view showing the valve aforesaid and parts associated therewith in side elevation for the most part, and as seen from a position to the right of Figure 2.

10 Figure 6 is a perspective view showing a toggle link of my invention by itself.

Figure 7 is a view showing a toggle frame member of my invention by itself and in perspective.

15 Figure 8 is a sectional view upon a central plane showing a spark plug such as my invention is designed to operate upon.

20 Referring now to the drawings wherein the same elements are identified by the same reference numerals wherever they appear in the several views, 10 designates a main frame whereby the various elements of the machine are properly supported relative to one another and which may be of any form suitable for that purpose; said 25 frame having a flat portion at its upper end designed to receive and support a cylinder casting 11 having two cylinders 12, 13 formed therein and within which pistons 14, 15 move as air under pressure is admitted to and exhausted from the spaces below said piston; said pistons having rods or plungers 16, 17 extending through holes provided in heads 18, 19 and which operate two oscillating levers which are both 30 pivotally supported upon a rod or shaft 20 the ends of which are supported in pedestals 21 which rise from the upper end of the frame at the sides thereof, and extend above said shaft and serve as supports for a transversely extending abutment rod 22.

35 The reference numeral 23 designates a lower gasket compressing lever which is centrally disposed upon the shaft 20 and the left hand end of which is acted upon and pushed upward by the piston 15 and plunger 17, and which lever is returned by a spring 24 operatively connected therewith. The right hand end of this lever is pivotally connected at 25 to a toggle link 26 which is 40 shown separately in Figure 6; and the lower end of this link is pivotally connected at 27 with the upper end of a link 28, the lower end of which is pivotally connected at 29 with the upper end of a lower gasket compressing plunger 30; which plunger extends through a passage provided in an upper gasket compressing plunger 31 which is 45 slidably in a suitable vertically arranged bearing 32 carried by the frame 10 of the machine. The links 26, 28 thus form a toggle 50 which when straightened as shown in Figures 1 and 2 places the machine in a condition such that upward movement of the piston 15 as air under pressure enters the

55 cylinders 13 beneath the piston will force the plunger 30 downward and apply pressure to the lower gasket —a— of the spark plug shown in Figure 8; the force being applied to the said gasket through the insulating member —b— as the lower end of 60 said plunger engages with the upper end of the insulating member and the direct and immediate effect of the pressure thus applied being to force the insulating member downward within the external metallic shell —c— of the plug which is being assembled; and which shell is supported by an annular anvil or abutment 33 which in turn is supported from the frame of the machine adjacent the lower end thereof. The plunger 30 is provided with a tubular floating pressure applying member 34 which will be described in detail hereinafter, and which forms the immediate insulator engaging member through which pressure is applied to the insulator as hereinbefore explained.

65 The reference numeral 35 designates an upper gasket compressing lever designed to force the plunger 31 downward to thereby compress the upper gasket —d— of the 70 spark plug through an annular die 36 at the lower end of said plunger and which forms the immediate force applying member to said gasket; the left hand end of said lever being forced upward by the plunger 16 as 75 air under pressure enters the cylinder 12 below the piston 14 therein, the lever being moved in a reverse direction by a spring 37, as will be understood. This lever 35 is bifurcated to provide, structurally, two levers 80 lying one upon each side of the lever 23, said parts being connected by a bridge portion 38; and the right hand end of this lever (or ends, strictly speaking, taking its bifurcated form into consideration) is pivotally connected at 39, 39 between pairs of 85 ears 40 at the upper end of a toggle frame 41 (which in effect is a toggle link shown as of the same length as the link 26), and which frame is shown separately in Figure 90 7. The lower end of this toggle frame is pivotally connected at 42, 42, with the upper ends of two links 43, 43 which enter slots provided in said frame and the positions of which are indicated by the numeral 44 in 95 Figure 2, and which links lie one upon either side of the link 28 (and are shown as of substantially the same length as said link 28); and the lower ends of these links are pivotally connected at 45, 45 with the 100 outer plunger 31 through which pressure is applied to the upper gasket —d— of the spark plug operated upon, as hereinbefore explained.

105 In view of the premises it will be seen 110 that the levers 23 and 35 are operatively connected, respectively, with the plungers 115 30 and 31, through two toggle mechanisms 120

which are separate and independent of one another; from which it follows that after a plug to be operated upon has been placed in the machine and the toggles have been straightened, as shown in Figures 1 and 2, each plunger is free to move independently of the other as air under pressure enters the cylinders 12, 13 and forces the pistons therein upward. Pressure is thus applied directly to the lower gasket —a— through the plunger 30 and the insulating member —b—; and directly to the upper gasket —d— through the plunger 31; and the fact that the former plunger is movable within and independently of the latter permits such movement of each plunger independently of the other as may be necessary to subject each gasket to the pressure found necessary to properly compress the same and form gas tight joints at each gasket.

As a matter of course the lower gasket is to a certain extent subjected to compression communicated from the upper gasket to the upper shoulder of the insulating member upon which it rests, and through said member to the lower gasket. As will hereinafter appear, however, the pressure applied to the upper gasket reaches its maximum slightly after the lower gasket has been fully compressed, and after the insulating member has completed its slight downward movement due to downward movement of the inner plunger 30; so that the pressure applied to the upper gasket by downward movement of the outer plunger 31 and which movement is slightly delayed relative to downward movement of the inner plunger will have little further compressing effect upon the lower gasket. Furthermore, the lower gasket is commonly made from asbestos fabric encased in or associated with a metallic covering or washer and is quite easily compressible, while the upper gasket is commonly made in the form of a ring of comparatively soft metal such, for example, as copper; so that the binding between the shell and insulating member produced by distortion of the upper gasket as pressure is applied thereto tends to limit the action of the outer plunger to the upper gasket, with the result that little or no pressure due to such outer plunger is communicated to the lower gasket; thus securing, as will be appreciated, independent compressing actions at both the lower and the upper gaskets. As a matter of practical importance, however, it is quite immaterial whether the lower gasket is regarded as compressed entirely by the inner plunger, or in part by the outer plunger; as, when the parts are properly adjusted so as to secure proper joints at the two gaskets it is unimportant how or in what particular way the pressure necessary to that end is secured and applied to the gaskets. Also, and as will be appreciated,

the operation of the device is independent of the particular kind of gaskets employed; and gaskets of other form than above referred to may be used in plugs assembled by the use of my invention.

The toggle frame 41 is provided with bearings 46 at its lower end which are offset relative to the plane of the pivotal connections 39, 42 and within which a transversely extending rod 47 is supported; and 70 48, 49 designate two toggle operating links the upper ends of which are pivotally connected with said rod, and the lower ends of which are pivotally connected with a transversely extending rod 49 supported at its 75 ends in bearings carried by a swinging frame 50, which in turn is pivotally supported at 51, 51 from the frame 10 of the machine. The bearing for the right hand end of this rod 49 is in the form of a loose sleeve 80 85 52 having a passage through which a rod 53 extends; and the lower end of this rod is connected with a foot operated lever 54 through a link 55, while the upper end of said rod 53 is connected with an arm 56 90 whereby an oscillating valve which controls the flow of air under pressure to and from the cylinders 12, 13 is operated. The rod 53 may slide through the passage aforesaid in the bearing 52; and 57 designates a 95 spring surrounding said rod and acting between the said bearing member and an abutment 58 upon the rod; whereby the rod may be moved further downward to thereby operate the air valve aforesaid after the toggles have been straightened and moved into the positions shown in Figures 1 and 2 through the links 48, 48; the movement of the valve during the straightening of the toggle links being insufficient to admit air 100 to the cylinders 12, 13, and the final movement thereof to admit air to the cylinders being permitted by the yielding action of the said spring 57. Thereafter and after the pistons 14, 15 have moved upward and pressure has been applied to the gaskets as aforesaid the springs 59, 59 extending between the links 48 and the abutment rod 22 105 will, when the treadle lever is released, act to return the pedal and break the toggle 110 connections and cause the toggle mechanism to assume the position shown in Figure 3, upward movement of the pedal lever being limited by an abutment 60 upon the rod 53 115 or otherwise as will be understood.

When the toggle connections are straightened as shown in Figures 1 and 2 the links 28 and 43, 43 will be slightly past their dead center positions and will rest against a stop 61 on the frame 10, against which they are held by the spring 57 as will be appreciated; in which position they remain while air is admitted to the cylinders 12, 13 by a further downward movement of the rod 53 which operates an air controlling valve and 120 125 130

during the compressing action to which the gaskets are subjected.

The toggle frame 41 being directly connected with the outside links 43, 43 it follows that the toggle mechanism associated with the lever 35 and through which said lever is connected with the outer plunger 31 through said frame and links will be straightened by the direct action of the links 48 as they swing said frame inward and about the pivotal connections 39 between it and the lever 35. During and simultaneous with this straightening action the second toggle connection between the lever 23 and the inner plunger 30 provided by the links 26, 28, will be straightened by engagement between the free end of a set screw 62 in threaded engagement with a bridge piece 63 of said frame and which free end engages the upper end of the central connecting link 28, which forms a part of said second mentioned toggle connection.

The upper ends of the links 28, 43, 43 as they move into their final positions when the toggles are straightened engage the heads of yieldable spring operated toggle breaking plungers 64 slidable in bearings upon the frame 10; from which it follows that the springs 65 associated with these plungers and which are compressed during such straightening movement will act to force the upper ends of said levers to the right, Figure 1, and break the toggles when the treadle lever 54 is released and the toggles are relieved from the holding-in action of the spring 57. Immediately after or simultaneously with such breaking action the springs 59 act to swing the frame 41 about the pivotal connections 39, and the toggle links 26, 28 are positively broken by the action of a screw 66 carried by the link 26 and the shank of which fits loosely in a recess 67 in the bridge portion 63 of said toggle frame; thus breaking both toggle mechanisms and placing the parts in the positions shown in Figure 3. The toggle breaking action is made more certain in the embodiment of my invention illustrated by tension springs 68, 68, the upper ends of which are connected with the abutment rod 22 and the lower ends of which are connected with a cross bar 69 secured to and moving with the outer plunger 31.

The cylinder casting 11 is provided with a vertically disposed valve seat, and the reference numeral 70 designates an oscillating disc valve operating upon said seat and with which the inner end of an operating shaft 71 is operatively connected; the arm 56 hereinbefore mentioned being secured to said shaft so as to communicate motion to the valve, as will be appreciated, and the valve being enclosed by a hollow cover 72 to thereby provide a valve chest

or chamber 73 within which the valve 70 is located. This valve may have various port arrangements, the one shown in dotted lines in Figure 5 being conventional, and comprising two recesses 74, 75 in the face of the valve separated by a bridge portion 96; whereby one or the other of said recesses at a time may be placed in communication with a port 77 leading into the cylinder 13 below the piston 15 therein. The valve has an opening 78 leading into the recess 74 so that air under pressure supplied through a pipe 79 to the valve chamber 73 may, upon slight further opening movement of the valve from the position shown and as the treadle lever 54 is farther depressed, flow from said chamber through said opening and through the recess 74 and passage 77 into the cylinder 13; while movement of the valve in a contrary direction (clockwise in Figure 5) as the toggle connections are broken will place the cylinder in question in communication with the atmosphere through said passage 77, the recess 75 and an exhaust port 80 and an exhaust pipe 81.

The cylinders 12, 13 are placed in communication with one another through a port 82 of comparatively small area; from which it follows that upward movement of the piston 14 may be delayed, slightly, relative to the piston 15; as the air to force said piston 14 upward must enter the cylinder 12 from the cylinder 13 through the restricted passage 82. The piston 15, however, will start up promptly as air is admitted to the cylinder 13; from which it follows that the inner plunger 30 which is operated by the piston 15 may be moved downward to compress the lower gasket of the plug slightly before the outer plunger 31 is moved downwardly by the piston 14 into engagement with the upper gasket, as hereinbefore explained.

The anvil or abutment 33 which receives the shell —c— of the plug being operated upon and forms the immediate support therefor is itself supported by and at the upper end of a hollow sleeve 83 carried by the frame of the machine, and within which sleeve a plunger 84 is housed and operates; said plunger being forced upward and against an internal stop flange 85 by a comparatively weak spring 86, and the same having an upwardly extending centering and discharging member 87 the upper end of which is shaped to conform to the lower end of the insulating member —b— of the plug. This supporting member acts (before the toggles are straightened) to support the plug with the enlarged central wrench receiving portion of the shell thereof slightly above the anvil 33, and acts to center the lower end of the insulating member relative to the shell and the shell relative to the abutment 33, and to guide the

insulator properly as it is forced slightly downward within the shell; the spring yielding freely to the superior force of the plunger 30, but acting as a discharge member to lift the plug up from the anvil to a slight extent when the toggle mechanisms are broken, and the plungers move up and away from the plug and into the position in which they are shown in Figure 3.

10 The inner plunger 30 as explained has a floating plunger 34, the upper end of which abuts at 88 against an internal shoulder of the plunger 30, and is held in place by a holding ring 89; said plunger being shaped 15 at its lower end to fit the upper end of the insulating member —b— of the plug operated upon and the same being yieldably held in a central position by a spring 90 the upper end of which enters a central 20 passage in the plunger 30 and the lower end of which enters a similar passage in the floating plunger 34.

From the above it follows that initial contact between the lower end of the floating plunger 34 and the upper end of the centering member 87 and the ends of the insulating member with which said members engage acts to center the insulating member relative to the plungers 30 and 34, 30 and to center the shell relative to the anvil 33; as the plug as a whole is then supported upon the spring 86 and the upper end of the floating plunger 34 is free to move sideways. Further downward movement of said 35 plungers 30 and 34 will move the shell downward and onto the seating surface at the upper end of the anvil 33, after which the upper and lower gaskets of the plug are compressed as hereinbefore explained.

40 Having thus described and explained my invention, I claim and desire to secure by Letters Patent:

1. In a device of the class described, two concentrically arranged reciprocating plungers; two pivotally supported operating levers; two toggle mechanisms intermediate said plungers and said levers, and through which said plungers are operated each independently of the other; means for simultaneously breaking and straightening said two toggle mechanisms; and means for operating said levers to thereby communicate movement to said plungers through said toggle mechanisms.

55 2. In a device of the class described, two concentrically arranged reciprocating plungers; two pivotally supported operating levers; two toggle mechanisms the lower ends of which are pivotally connected one with each of said plungers, and the upper ends of which are pivotally connected one with each of said levers; means for simultaneously breaking and straightening said two toggle mechanisms; means operated by air under pressure for operating said plunger operat-

ing levers; and means for controlling the flow of air under pressure to and from said operating means.

3. In a device of the class described, two concentrically arranged plungers; two pivotally supported operating levers; two toggle mechanisms the lower ends of which are pivotally connected one with each of said plungers, and the upper ends of which are pivotally connected one with each of said levers; means for simultaneously breaking and straightening said two toggle mechanisms; means operated by air under pressure for operating said plunger operating levers; and means operated by said toggle operating means for controlling the flow of air under pressure to and from said operating means.

4. In a device of the class described, two concentrically arranged reciprocating plungers; two pivotally supported operating levers; two toggle mechanisms the lower ends of which are pivotally connected one with each of said plungers, and the upper ends of which are pivotally connected one with each of said levers; a foot operated lever operatively connected with both said toggle mechanisms to thereby simultaneously break and straighten the same; means operated by air under pressure for operating said plunger operating levers; means for controlling the flow of air under pressure to and from said air operated means; and means operated by said foot operated lever for operating said air flow controlling means to thereby control the flow of air under pressure to and from said air operated means.

5. In a device of the class described; two concentrically arranged reciprocating plungers; two pivotally supported operating levers; two toggle mechanisms the lower ends of which are pivotally connected one with each of said plungers, and the upper ends of which are pivotally connected one with each of said levers; link mechanism through which said toggle mechanisms may be simultaneously broken and straightened; a foot operated lever operatively connected with said link mechanism; means operated by air under pressure for operating said plunger operating levers; a valve for controlling the flow of air under pressure to and from said air operated means; and a connection between said foot operated lever and said valve and through which said valve is operated.

6. In a device of the class described, two concentrically arranged reciprocating plungers; two pivotally supported operating levers; two toggle mechanisms the lower ends of which are pivotally connected one with each of said plungers, and the upper ends of which are pivotally connected one with each of said levers; means operated by air under pressure for operating said plunger operating levers; a valve for controlling

the flow of air under pressure to and from said air operated means; a foot operated lever operatively connected with said valve; means for simultaneously breaking and straightening said two toggle mechanisms; and link mechanism operated by said foot-operated lever and adapted to operate said breaking and straightening means.

7. In a device of the class described, two concentrically arranged reciprocating plungers; the movements of which occur in unison, and in the same direction along their common axis; two pivotally supported operating levers; two cylinders having each a piston operating therein, and which pistons are operatively connected one with each of said levers; a valve adapted to control the flow of air under pressure to and from said cylinders; and mechanism through which movement of said levers is communicated to said plungers.

8. In a device of the class described, two reciprocating plungers; two pivotally supported operating levers; two cylinders having each a piston operating therein, and which pistons are operatively connected one with each of said levers; a valve adapted to control the flow of air under pressure to and from said cylinders; two toggle mechanisms intermediate said levers and said plungers and through which said plungers are operated from said levers; means whereby one of said toggle mechanisms may be broken and straightened; and means operated by said breaking and straightening means for breaking and straightening the other of said toggle mechanisms.

9. In a device of the class described, two reciprocating plungers; two pivotally supported operating levers; two cylinders having each a piston operating therein, and which pistons are operatively connected one with each of said levers; a valve adapted to control the flow of air under pressure to and from one of said cylinders; a passage through which said cylinders are placed in communication with one another; and mechanism through which movement of said levers is communicated to said plungers.

10. In a device of the class described, two concentrically arranged reciprocating plungers; two pivotally supported operating levers; two cylinders having each a piston operating therein, and which pistons are operatively connected one with each of said plungers; a passage through which said cylinders are placed in communication one with the other; a valve for controlling the flow of air under pressure into and out from one of said cylinders; and a foot operated lever operatively connected with said valve to operate the same.

11. In a device of the class described, two concentrically arranged reciprocating plungers; two pivotally supported operating

levers of different lengths; two cylinders having each a piston operating therein, and which pistons are operatively associated one with each of said levers; a passage through which said cylinders are placed in communication one with the other; a valve for controlling the flow of air under pressure into and out from one of said cylinders; and means through which each of said levers communicates motion to one only of said plungers, so that each plunger is free to operate independently of the other.

12. In a device of the class described, two concentrically arranged reciprocating plungers; two pivotally supported operating levers of different lengths; two cylinders having each a piston operating therein, and which pistons are operatively associated one with each of said levers; a valve for controlling the flow of air under pressure to and from said cylinders; and means through which each of said levers communicates motion to one only of said plungers, so that each plunger is free to operate independently of the other.

13. In a device of the class described, two cylinders in communication with one another; two pistons operating one in each of said cylinders; a valve adapted to control the flow of air under pressure into and out from one of said cylinders; a foot operated lever for operating said valve; two concentrically arranged reciprocating plungers adapted to operate upon a spark plug, and which plungers are operated independently of one another one by one and the other by the other of said pistons; and means through which said plungers are operated as aforesaid, one from each of said pistons.

14. In a device of the class described, two concentrically arranged reciprocating plungers adapted to operate upon a spark plug; two pivotally supported operating levers for said plungers; two toggle mechanisms the lower ends of which are pivotally connected one with each of said plungers, and the upper ends of which are pivotally connected one with each of said levers; means for simultaneously breaking and straightening said toggle mechanisms; spring operated plunger mechanism engaging said toggle mechanisms to assist in the breaking thereof; means operated by air under pressure for operating said plunger operated levers; and means for controlling the flow of air under pressure to and from said air operated means.

15. In a device of the class described; two concentrically arranged reciprocating plungers; two pivotally supported operating levers; two toggle mechanisms the lower ends of which are pivotally connected one with each of said plungers and the upper ends of which are pivotally connected one with each of said levers; means for simul-

- 5aneously breaking and straightening said toggle mechanisms; spring operated plunger mechanism engaging said toggle mechanisms to assist in the breaking thereof; and 5 means for operating said levers to thereby operate said plungers through said toggle mechanisms.
16. In a device of the class described, two concentrically arranged reciprocating plungers adapted to operate upon a spark plug; two pivotally supported operating levers for said plungers; two toggle mechanisms the lower ends of which are pivotally connected one with each of said plungers, and the 10 upper ends of which are pivotally connected one with each of said levers; link mechanism operatively connected with one of said toggle mechanisms and adapted to break and straighten the same; means whereby the 15 other toggle mechanism is operated from said link operated toggle mechanism; a foot operated lever operatively connected with said link mechanism; air operated means for operating said plunger operating levers; a 20 valve for controlling the flow of air under pressure to and from said air operating means; and means whereby said valve is operated by said foot operated lever.
17. In a device of the class described, two concentrically arranged reciprocating plungers; two pivotally supported operating levers; two toggle mechanisms the lower ends of which are pivotally connected one with each of said plungers, and the upper 25 ends of which are pivotally connected one with each of said levers; link mechanisms operatively connected with one of said toggle mechanisms and adapted to break and straighten the same; means whereby the 30 other toggle mechanism is operated from said link operated toggle mechanism; a foot operated lever operatively connected with said link mechanism; and means controlled by said foot operated lever for operating 35 said first mentioned levers.
18. In a device of the class described, two concentrically arranged reciprocating plungers movable in unison to and fro along their common axis, and which plungers are 40 adapted to operate independently of one another upon a spark plug; two pivotally supported levers independent of one another and which levers are operatively connected one with each of said plungers; two cylinders; two pistons located one within each 45 of said cylinders, and which pistons are operatively connected one with each of said levers; a valve adapted to control the flow of air under pressure to and from said cylinders; and means for operating said valve.
19. In a device of the class described, two concentrically arranged reciprocating plungers adapted to operate independently of one another upon a spark plug; two pivotally supported operating levers for said 50
- plungers; two cylinders; two pistons operating one within each of said cylinders, and which pistons are operatively connected one with each of said levers; a valve for controlling the flow of air under pressure to 55 and from one of said cylinders; two toggle mechanisms separate and independent of one another and the lower ends of which are pivotally connected one with each of said plungers, and the upper ends of which are pivotally connected one with each of said levers; and a foot operated lever operatively connected with said valve and with the said toggle mechanisms and whereby said toggle mechanisms and said valve are 60 operated.
20. In a device of the class described, two concentrically arranged reciprocating plungers; two pivotally supported operating levers; two toggle mechanisms the lower 65 ends of which are pivotally connected one with each of said plungers, and the upper ends of which are operatively connected one with each of said levers; two cylinders; two pistons operating one within each of said 70 cylinders, and which pistons are operatively associated one with each of said levers; a valve for controlling the flow of air under pressure to and from said cylinders; link mechanism operatively connected with said 75 toggle mechanisms to simultaneously break and straighten said mechanisms; a foot operated lever; a valve operating rod intermediate said foot operated lever and the valve aforesaid; and a spring associated 80 with said valve operating rod and through which said link mechanism is operated from said rod.
21. In a device of the class described, two concentrically arranged reciprocating plungers; two pivotally supported operating levers; two toggle mechanisms the lower ends of which are pivotally connected one with each of said plungers and the upper 85 ends of which are operatively connected one with each of said levers; means for operating said levers to thereby communicate movement to said plungers through said toggle mechanisms; link mechanism operatively connected with said toggle mechanisms to simultaneously break and straighten said mechanisms; a foot operated lever; an operating rod intermediate said foot operated lever and the operating means aforesaid for said first mentioned levers; and a 90 spring associated with said operating rod and through which said link mechanism is operated from said rod.
22. In a device for operating upon spark plugs, an annular anvil adapted to receive and support the shell of a plug; a spring pressed plunger concentric with said anvil and having a support arranged to engage the lower end of the insulating member of the 95 plug; a reciprocating plunger the lower end 100

of which is adapted to engage the upper end of the insulating member aforesaid; and means for operating said last mentioned plunger.

23. In a device for operating upon spark plugs, a hollow supporting sleeve; an annular anvil supported by said sleeve and adapted to receive and support the shell of a plug; a reciprocating plunger operating within said sleeve and having an upwardly extending portion arranged to engage the lower end of the insulating member of the plug; a spring acting upwardly upon said plunger; a reciprocating plunger the lower end of which is adapted to engage the upper end of the insulating member aforesaid; and means for operating said last mentioned plunger.

24. In a device for operating upon spark plugs, a hollow supporting sleeve; an annular anvil supported by said sleeve and adapted to receive and support the shell of a plug; a hollow reciprocating plunger operating within said sleeve, and having an upwardly extending portion arranged to engage the lower end of the insulating member of the plug; a spring arranged within said plunger and acting upwardly thereupon; a reciprocating plunger the lower end of which is adapted to engage the upper end of the insulating member aforesaid; and means for operating said last mentioned plunger.

25. In a device for operating upon spark plugs, an annular anvil adapted to receive and support the shell of the plug; a spring pressed plunger concentric with said anvil and having a support arranged to engage

the lower end of the insulating member of the plug; a reciprocating plunger and means for operating the same; and an auxiliary floating plunger carried by said reciprocating plunger and the lower end of which is adapted to engage the upper end of the insulating member aforesaid.

26. In a device for operating upon spark plugs, an annular anvil adapted to receive and support the shell of a plug; a spring pressed plunger concentric with said anvil and having a support arranged to engage the lower end of the insulating member of the plug; a reciprocating plunger and means for operating the same; an auxiliary plunger carried by said reciprocating plunger and free to move laterally relative thereto, and the lower end of which is adapted to engage the upper end of the insulating member aforesaid; and a spring between said reciprocating and auxiliary plungers and adapted to hold said auxiliary plunger in a normally central position.

27. In a device for operating upon spark plugs, an annular anvil adapted to receive and support the shell of a plug; a reciprocating plunger and means for operating the same; an auxiliary plunger carried by said reciprocating plunger and movable laterally relative thereto, and the lower end of which is adapted to engage the upper end of the insulating member aforesaid; and a spring associated with said reciprocating and auxiliary plungers and adapted to hold said auxiliary plunger in a normally central position.

In testimony whereof I affix my signature,
HECTOR RABEZZANA.
